WINDOW SCREEN

John Clifford Gieser, Cardington, Ohio

Application December 27, 1939, Serial No. 311,176

4 Claims. (Cl. 156—39)

This invention relates broadly to screens of the type employed particularly for use in connection with windows, and more particularly to that type of screen including a web or sheet of flexible foraminous material attached at one end to a spring roller and equipped at the other end thereof for attachment to a window sash.

Among the objects of the present invention is to provide a screen of this type which may be readily installed and which, generally, is an improvement upon such screens.

The invention together with its objects and advantages will be best understood from a study of the following description taken in connection with the accompanying drawings wherein:

Figure 1 is an elevational view illustrating the application of the screen with the window sash in raised position.

Figure 2 is a fragmentary vertical sectional view taken substantially on the line 2—2 of Fig. 1.

Figure 3 is an end elevational view of the screen and housing therefor.

Figure 4 is a fragmentary detail sectional view through the spring-equipped end of the roller, and

Figure 5 is a detail sectional view taken substantially on the line 5—5 of Fig. 1.

Referring more in detail to the drawings it will be seen that in the preferred embodiment of the invention the same comprises an oblong housing 5 embodying an oblong frame having a top 6, ends 7, and a bottom 8; the bottom 8 being in the form of a rectangular plate equipped at opposite ends thereof with flanges 9 to which are riveted or otherwise secured as at 10 the sides 7 of the frame.

Completing the housing there is disposed at the outer side of the frame 7 an angular wall 11 that is integral with the outer longitudinal edge of the plate 8. The wall 11 extends vertically upwardly from the plate 8 and then is curved inwardly towards the top 6 of the frame, with the upper edge of the wall in intimate contact with the longitudinal edge of the top member 6 of the frame, and may be welded or otherwise positively united therewith as found desirable.

It will be seen that this construction and arrangement provide for openings 12 at opposite sides of the housing whereby access may be had to the screen and the roller therefor.

The sides 7 of the frame portion of the housing are equipped adjacent one vertical edge thereof to receive the pintles of a roller 13 whereby said roller may be easily and quickly mounted in position.

As shown in Fig. 14 the roller embodies a core member 14 and an outer tubular member 15 that is rotatable with the core and is normally urged to rotate in one direction relative to a shaft 16 through the medium of a coil spring 17 that is convoluted about the shaft 16 that extends from one end of the core 14 through one end of the complete roller. The spring 17 is suitably anchored to the core 14 and to one end of the shaft 16, and the tubular part 13 of the roller is equipped to receive one end of the shaft 16 as shown. Thus spring 17 will, as previously stated, cause the parts of the roller as a unit to rotate relative to the shaft for winding on the roller the web or sheet 18. The web or sheet 18 is of flexible foraminous material, and at its free end is provided with a reinforcing bar 19.

Bar 19 is provided with eye-bolts 20 adapted to be engaged with hooks 21 provided on the lower rail of the sliding window sash 22 for detachably connecting the screen with the window sash.

Also mounted in the frame of the housing 5 is a guide roller 23 over which the sheet 18 is trained as clearly shown in Figs. 2 and 3.

In actual practice, the frame portion of the housing 5, and which is slightly longer than the wall 11 of said housing, sits on the window sill between the stops 23, 24, and the entire housing structure is releasably anchored in position through the medium of pointed anchoring lugs 25 that are pivoted to the top 6 of the frame portion of the housing as at 26. The pointed ends of the anchoring prongs 25 bite into the side rails 27 of the window frame and thus serve to properly anchor the housing in position and against the housing being pulled upwardly incidental to a raising of the window sash 22.

From the above it will be seen that when the device is properly applied and the screen sheet 18 connected in the manner shown and described to the lower rail of the sliding sash 22, movement of the sash 22 to a raised position will cause the screen web 18 to pay out and thus cover the opening caused by the raising of the window sash.

Manifestly, as the sash 22 moves downwardly to a closed position the screen web 18 will wind on the roller 13.

It is thought that a clear understanding of the construction, operation, utility and advantages of a window screen embodying the features of the present invention will be had without a more detailed description thereof.

Having thus described the invention what is claimed as new is:

1. In a window screen, an elongated housing member adapted to be positioned on a window sill between the vertical rails of a window frame and equipped with means for engaging such rails to anchor said housing in place, a roller journaled in said housing, and a screen web windable on said roller, said web having a free end reinforced and equipped with means for detachably connecting said end to the lower rail of a sliding sash; and said housing comprising a relatively broad flat base plate, a frame rising from said base plate and extending for substantially the full length of said base plate and including a top member, the members of said frame being substantially half the width of said base plate, and a wall plate extending upwardly from the longitudinal edge of the base plate farthest remote from said frame and having the upper portion thereof biased toward said frame with the upper edge in meeting contact with the top member of said frame.

2. In a portable screen, a base plate having upstanding flanges at opposite ends thereof and extending from about the longitudinal median of said plate to one longitudinal edge of the plate, a frame having top and end members, said end members at the lower ends thereof being secured to said flanges, a spring roller supported between the end members of said frame, a flexible foraminous web windable on said roller, and a wall-forming plate extending from the second longitudinal edge of said base plate to the top member of said frame.

3. In a portable screen, a base plate having

upstanding flanges at opposite ends thereof and extending from about the longitudinal median of said plate to one longitudinal edge of the plate, a frame having top and end members, said end members at the lower ends thereof being secured to said flanges, a spring roller supported between the end members of said frame, a flexible foraminous web windable on said roller, and a wall-forming plate extending from the second longitudinal edge of said base plate to the top member of said frame, and anchoring lugs pivoted at one end thereof to the top member of the frame adjacent opposite ends of said top member.

4. In a portable screen, a base plate having upstanding flanges at opposite ends thereof and extending from about the longitudinal median of said plate to one longitudinal edge of the plate, a frame having top and end members, said end members at the lower ends thereof being secured to said flanges, a spring roller supported between the end members of said frame, a flexible foraminous web windable on said roller, and a wall-forming plate extending from the second longitudinal edge of said base plate to the top member of said frame, and anchoring lugs pivoted at one end thereof to the top member of the frame adjacent opposite ends of said top member, and said web having a free edge provided with a transversely extending reinforcing bar equipped with means for attaching said web at said edge to the rail of a sliding window sash.

JOHN CLIFFORD GIESER.
